UNITED STATES PATENT OFFICE.

AUGUST W. WARSEN, OF NEW YORK, N. Y.

CRUSHER.

1,130,864.

Specification of Letters Patent.

Patented Mar. 9, 1915.

Application filed May 20, 1914. Serial No. 839,779.

To all whom it may concern:

Be it known that I, AUGUST W. WARSEN, a citizen of the United States, and a resident of the city of New York, borough of Brooklyn, in the county of Kings and State of New York, have invented a new and Improved Crusher, of which the following is a full, clear, and exact description.

The invention relates to crushers of the jaw type; and the object thereof is to provide a simple, strong, and inexpensive crusher by means of which material can be crushed to varying sizes, not exceeding a predetermined maximum. I attain the above object by providing a frame having a fixed jaw and an oscillating lever in the frame having a jaw adapted to coact with the fixed jaw of the frame, the said lever being adjustably mounted in said frame and adapted to be reversed in the same. Furthermore, the means for actuating said lever are so connected to the same as to prevent a rupture in any of the moving parts of the crusher when an object of high resistance is located between the crushing jaws.

The invention consists of the construction and combination of parts to be more fully described hereinafter and fully set forth in the claims.

Before proceeding to a more detailed description of my invention it must be clearly understood that the structure herein disclosed is an improvement on my Patent No. 1,101,480.

Referring to the drawing, 1 represents the main frame, the transverse part 2 of which carries the stationary or fixed jaw plate 3. The main frame 1 is provided with an upper and a lower bearing 4 and 5, the lower bearing being adjustable by means of a screw 6. The purpose of the two bearings is to permit two different positions to the shaft 8 of the swinging lever 7 whereby the crushing material may be of a definite size or of variable sizes. When the swinging lever is in position shown in full lines in the drawing, the crusher is adapted to crush the material to a predetermined size. When the swinging lever 7 is in the position shown in a dash-and-dot line in the drawing, the crusher is adapted to crush the material to variable sizes, as more clearly described in my Patent No. 1,101,480. The swinging lever 7 also carries a jaw plate 3' which is

adapted to face the plate 3 in any position 55 of said lever.

A pitman 9 is mounted on an eccentric shaft 10 bearing transversely of the main frame and which also carries a fly or balance wheel 11 and a pulley, not shown, for transmitting the movement to the eccentric shaft. The main part of the pitman extends downwardly into the main frame; and on the side facing the swinging lever 7 it is provided with a toggle bearing 12 engaged by one end 65 of a toggle 13, the other end of said toggle being engaged by another toggle bearing 12 provided in the swinging lever 7. The other side of the pitman is provided with a recess 14 extending parallelly to the axis of the shaft 10 and nearer thereto than the bearing block 12 in the pitman. Bearing snugly in the recess 14 is a projection 15 of an arm 16, the main part of which arm extends upwardly adjacent the pitman 9 and to which 75 it is connected by compression springs 17 mounted on bolts 18 passing through said arm 16 and through an upward extension 19 provided on the pitman. The downwardly extending portion 20 of the arm 16 carries 80 a toggle bearing 12 and is engaged by one end of the toggle 13, the other end of which is engaged by a toggle bearing provided in a toggle block 21 which may be adjustably mounted in the main frame 1.

It will be noted that the toggle bearing 12 in the arm 16 is below the bearing point of the arm 16, and, therefore, the arm 16 is a lever of the first class, the fulcrum of which is in the recess 14. It will also be noted that 90 under no circumstances can the axes of the toggles through their bearings and the fulcrum of the arm 16 come into a straight line. This construction permits the arm 16 to turn on its projection 15 in the recess 14 of the 95 pitman when an object of high resistance falls between the jaw plates 3 and 3' during the movement of the crank shaft 10. That is to say, when such an object is engaged between the jaws, the swinging lever 7 remains immovable while the arm 16 oscillates during the movement of the pitman. The compressive resistance of the springs 17 is less than the resistance to rupture of the toggles 13, and, therefore, no damage can be 100 done to any of the moving parts of the crusher when an object of high resistance falls between the jaw plates 3 and 3'.

From the foregoing description, taken in connection with the accompanying drawing, the advantage of the construction and operation of the device shown will be readily understood by those skilled in the art to which the invention pertains; and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. In a crusher,—a frame; a jaw carried by the frame; a lever mounted to oscillate in the frame; a jaw carried by the lever; a crank shaft in the frame; a pitman on the crank; a toggle intermediate the pitman and the lever; a second toggle on the other side of the pitman associated with the frame; and means positioned between the said second toggle and the pitman adapted to maintain said lever immovable, while the pitman moves, when an object of high resistance enters between the crushing jaws.

2. In a crusher,—frame; a jaw carried by the frame; a lever mounted to oscillate in the frame; a jaw carried by the lever; a crank shaft in the frame; a pitman on the crank; a toggle intermediate the pitman and the lever; a second toggle on the other side of the pitman associated with the frame; means between the pitman and said last mentioned toggle including resilient members whereby said lever is adapted to remain immovable, while the pitman moves, when an object of high resistance enters between the crushing jaws.

3. In a crusher,—a frame; a crushing jaw in the frame; a lever mounted to oscillate in the frame; a jaw in the lever; a pitman in the frame; means for actuating the pitman; a toggle between the pitman and the lever; a second toggle on the opposite side of the pitman associated with the frame; an arm mounted to oscillate on the pitman engaging said second toggle; and resilient means normally preventing the oscillation of said arm on the pitman, the resistance of said resilient means being such as to permit the lever to remain immovable, while the pitman moves, when an object of high resistance enters between the jaws.

4. In a crusher,—a frame; a jaw in said frame; a lever mounted to oscillate in the frame; a jaw carried by the lever; means for oscillating the lever; and means associated with said means for oscillating the lever, positioned exteriorly of said lever, whereby the said lever remains immovable during the

movement of said means for oscillating the lever when an object of high resistance enters between the jaws.

5. In a crusher,—a frame; a jaw in said frame; a lever mounted to oscillate in the frame; a jaw carried by the lever; means for oscillating the lever; an arm associated with said means for oscillating the lever; and a resilient member normally maintaining the arm against said means for oscillating the lever, said resilient member preventing injury to any moving part of the crusher when an object of high resistance enters between the crushing jaws.

6. In a crusher,—a frame; a crushing jaw in said frame; a lever mounted to oscillate in the frame; a crushing jaw carried by the lever; a pitman for oscillating the lever; an arm pivotally associated with the pitman; and a spring normally preventing the pivotal movement of said arm on the pitman, the resistance of said spring being such that said arm will only move when an object of high resistance is engaged between the crushing jaws.

7. In a crusher, a frame, a crushing jaw in said frame, a lever mounted to oscillate in the frame, a crushing jaw carried by the lever, a pitman for oscillating the lever, an arm pivotally associated with the pitman, said pivot of the arm being located below the point of oscillation of the pitman, and springs normally preventing the pivotal movement of said arm on the pitman, said springs being located above the point of oscillation of the pitman, the resistance of said spring being such that said arm will only move on its pivot when an object of predetermined resistance is engaged between the crushing jaws.

8. In a crusher, a frame, a jaw carried by the frame, a lever mounted to oscillate in the frame, a jaw carried by the lever, a crank shaft in the frame, a pitman on the crank, a toggle intermediate the pitman and the lever, a second toggle on the other side of the pitman associated with the frame, an arm positioned between said second toggle and the pitman and pivotally associated with the pitman, the axis of said pivot being below said crank but above said toggles, and resilient means connecting said arm and the pitman whereby the lever remains immovable while the pitman moves when an object of high resistance enters between the crushing jaws.

In testimony whereof I have signed my name to this specification in the presence of two subscribing witnesses.

AUGUST W. WARSEN.
